United States Patent Office

Des. 205,475
Patented August 9, 1966

205,475

PORTABLE TELEVISION RECEIVER

Frank M. Grunwald, North Syracuse, and John C. Adams,
Liverpool, N.Y., assignors to General Electric Com-
pany, a corporation of New York

Filed Oct. 29, 1964, Ser. No. 82,375

Term of patent 14 years

(Cl. D56—4)

FIG.1

FIG.2

FIG.3

FIG.4

FIG.5

FIG.6

FIGURE 1 is a perspective view of a portable television receiver embodying our new design;

FIGURE 2 is a front elevational view on a reduced scale, with the handle in carrying position and the antenna in telescoped position;

FIGURE 3 is a side elevational view on the same scale as in FIGURE 1;

FIGURE 4 is a side elevational view showing the side opposite that shown in FIGURE 3;

FIGURE 5 is a top plan view on the same scale as in FIGURE 1; and

FIGURE 6 is a bottom plan view thereof.

We claim:

The ornamental design for a portable television receiver, as shown.
